FLAME-DIFFUSER AND HEAT-RETAINER
DEVICE FOR FURNACES

George Faulds, Philadelphia, Pa.

Application January 3, 1939, Serial No. 248,940

17 Claims. (Cl. 122—20)

This invention relates generally to heating installations including an intermittently-fired furnace having a combustion chamber above the fire box, said chamber including an axially located flame-diffuser and heat-retainer means designed to effect substantially complete combustion of the available heat units contained in the fuel.

More specifically, the present improvements have reference to flame-diffusing and heat-retaining devices of the type disclosed in my co-pending application filed August 9, 1938, under Serial No. 223,781, and has for general objects certain desirable improvements and variations whereby the thermal efficiency of such devices is enhanced, their assembly and adaptation to different sizes and shapes of heater furnaces facilitated, more effective diffusion of the flame is promoted, and a novel water back is associated therewith.

Subsidiary objects and ancillary advantages of this invention, including specific features of construction and assembly refinements, will be hereinafter pointed out or become apparent from the following description of typical embodiments of said invention, when considered in conjunction with the accompanying sheets of illustrative drawings; while the novel items are more particularly expressed in the concluding claims.

With the foregoing in view the present invention essentially consists in the features of construction, combinations and arrangements of parts hereinafter set forth.

In the drawings:

Fig. I is a view partly in elevation, but mainly in vertical section, of a domestic heating furnace including one type of the improved flame-diffusing and heat-retaining means of the present invention.

Fig. II is a horizontal section on the plane designated II—II in Fig. I.

Fig. III is a horizontal section on the plane III—III of Fig. I, or taken through the flame-diffusing and heat-retaining device.

Fig. IV is a similar plan section to the preceding, but taken on the plane designated IV—IV in Fig. I.

Fig. V is a fragmentary detail elevation of partially-overlapping arcural-baffles included in the structure, and hereinafter fully described.

Fig. VI is a perspective view of one of the complemental sections comprised in the flame-diffusing and heat-retaining device.

Fig. VII is a perspective view of an inverted

one-half of the crown-portion of the improved device.

Fig. VIII is a perspective view of one of the baffles.

Figs. IX and X are perspective views of substitute blocks for elevating the crown of the device in accommodating this invention to different depths of combustion chambers.

Fig. IX is a plan section illustrating the adaptation of this invention to a rectangular type furnace, and taken approximately on the plane designated XI—XI in Fig. XII.

Fig. XII is a vertical section on the plane XII—XII of Fig. XI.

Fig. XIII is a vertical staggered-section, taken as indicated by the lines and arrows XIII—XIII in Figs. XI and XII, but drawn to a larger scale for better illustration of certain details herein-after fully explained.

Fig. XIV is a fragmentary elevation viewed in the direction of the arrows XIV—XIV in Fig. XIII, showing a special arrangement of baffles along the back wall of the heat retainer structure.

Fig. XV is a horizontal corner-section taken on the plane XV—XV in Fig. XII, but drawn to a larger scale.

Fig. XVI is a perspective view of the rectangular type flame-diffuser and heat-retainer with the crown thereof removed.

Fig. XVII is a perspective view of a corner baffle hereinafter fully described.

Fig. XVIII is a fragmentary perspective view illustrating how the corner structure of Fig. XVI may be interlocked, at the upper edge, by a special block arranged to elevate the crown; and,

Fig. XIX is a perspective view of said special block.

In the drawings, and referring more particularly to Figs. I, XI and XII, a conventional type of intermittently-fired hot-water heater or furnace is comprehensively designated 1; that shown on the first-mentioned figure being of circular cross-section and that in the latter two figures of rectangular cross-section. Each heater or furnace includes a refractory lined fire pot 2; a heat transfer or jacketed combustion chamber 3 with upper and lower access doors 4, 5, respectively; and a water head 6 defining passes to the outlet flue 7. The furnace is fired by a conventional type oil burner 8 having a discharge nozzle 9 projecting into the fire pot 2. All of the foregoing are in accordance with known practice and form no part of the present invention.

55

Referring now more particularly to Figs. I-X, inclusive, which illustrate a typical embodiment of this invention, the baffle and heat retaining device 10 has the form of a massive cage preferably of metal which is positioned axially over the fire pot, said cage being of a diameter greater than that of the fire pot 2 but of less girth and height than the combustion chamber of the furnace. As a consequence, there is defined a 10 perimetric space within the furnace between the device 10 and the furnace wall as well as a space above the device comprises complementary body sections 11 of substantial cast iron to ensure stability when assembled; each said section being formed with spaced and longitudinally-aligning upper and lower outwardly-convergent slots 12, 13, respectively, defined by vertical and horizontal rails preferably of the cross-section shown in Fig. IV at 11'; as well as top and bottom 15 of arcual projections 14, 15, at each side thereof, with one of the latter having an offset extension 16. Each section 11 is also provided medially of its height, at one side, with a lateral lug 17 and at the opposite side with spaced similar lugs 18, respectively adapted for interengagement "hinge-fashion" with the corresponding lugs of the flanking sections 11 and connected together by pins 19, when the retainer device 10 is assembled, as readily understood from Fig. I, 20 said retainer seating on an annular plate or ring 20 of complementary halves for easy passage through the access door 5 and disposition centrally over the fire pot 2.

Seating on the top of the baffle and heat retainer device 10 and engaged over the abutting edges of the arcual projections 14 are spacer blocks 21, best shown in Figs. IX and X. Each block 21 is formed with a lower arcual channel 22 of a cross-section for easy engagement over 25 the projections 14, and an upper tapering-section groove or fork-portion 23 which, when the blocks 21 are placed around the top of the retainer 10, as clearly understandable from Figs. I and III, jointly afford substantial support for 30 a removable top or crown 24. From Figs. IX and X, it will be understood the blocks 21 may be made in sets corresponding in number with the retainer body sections 11, so that the abutting arcual projections 14 are all interengaged 35 with capacity for relative movement incident to expansion and contraction: also that they are producible in sets of different heights for usage in varying depths of combustion chambers 3.

The crown-piece 24 comprises complementary concavo-convex halves 25, Figs. II and VII, which individually embody a circumferential semi-annular rib 26, and radial grooves 27 in the concave-face merging into spacedly-related apertures 28 around a central semi-circular cut-out 40 having a projecting rib 29. When the two halves 25 are placed together on the top of the retainer device 10, the semi-circular cut-outs jointly form an axial aperture 30 through the crown-piece 24 for seating reception of a water-back 31. This 45 water-back 31 is, preferably, of hollow hemispherical cross-section, with a concentric groove 32 projecting from the convex face for engagement over the projecting rib 29 of the retainer crown 24; and axially of the convex portion is 50 suitably attached a service or inlet connection 33 for the water to be heated in the back 31, while an outlet pipe 34 is correspondingly secured to the flat top 35 of said back for discharge purposes. In the event the outlet pipe 34 should 55 project into the combustion chamber 3 at a lower

level than shown, or in case the water head 6 is at a lower level, provision is made for attachment of said pipe to the water-back 31 by removal of a screw plug 36 and its connection into the correspondingly-threaded hole 38 in the water-back top 35. In addition, the water-back 31 is provided interiorly with radial projections or blades 39, preferably of the semi-crescent shape shown and functional to increase heat 10 conduction to the water contained in said back. 5

Comparatively heavy cast-iron radial baffles 40 are arranged around the crown 24 in edge-overlapping relation to induce a "whorling" action, or rotary turbulence, in the flow of the products 15 of combustion about the upper part of the heat-retainer device 10, said baffles also serving to effectively prevent short-circuiting of unconsumed fuel particles below the combustion chamber top. Each baffle 40, as best shown in Figs. 20 V and VIII, embodies an arcual inverted channel-section base 41 and a tangential blade 42 pitched at an angle to the horizontal with a reinforcing fillet 43 thereunder; said blade having the radial edges 44, 45 reversely or quarter-rounded downwardly and upwardly, with the circumferential edge 46 similarly rounded downwards. Thus it will be apparent that, when adjoining baffle radial edge portions 44, 45 are 25 brought into overlapping relation, with the bases 30 41 in abutment, as shown to best advantage in Fig. V, there will be formed around the crown 24 a series of regularly spaced angularly-directed choke passages 47 collectively serving to induce 35 checked spiral-flow of combustible gases from below said series to the upper region thereof, while the respective rounded edges prevent short-circuiting of said gases thereat.

By reason of the foregoing construction, it will be seen that during the active periods of the 40 burner, the hot products of combustion are obliged to pass from the fire pot and through the cage, while the vanes 40 which extend into close proximity to the furnace wall, serve to diffuse and gyrate the gas and at the same time 45 retard their escape from the space between the device 10 and the furnace wall to facilitate heat absorption by said device. On the other hand, during the off periods of the burner, the vanes operate to suppress the gases and thereby 50 serve the heat previously stored in the cage. 55

Referring to Figs. XI-XIX, inclusive, which illustrate the application of the present improvements to a rectangular type boiler, all parts having their equivalents in the preceding description will be similarly designated with a "prime" exponent added for illustrative differentiation, and to avoid unnecessary repetitive explanation. The combustion chamber 3' being rectangular in cross-section, the baffle and heat 60 retainer 10' comprises a slotted back wall 48, similar side walls 49, and preferably a blank or solid front wall 50; said parts being assembled, connected and secured together by offsets 16', lateral apertured lugs 17', 18', and pins 19'; 65 while the retainer 10' seats on a rectangular base plate 20'. The spacer blocks 21', with the exception of the corner blocks 51, are like those previously described. Each corner block 51 consists of a substantial body having a rectangularly-directed channel 52 in the lower part, and of suitable proportions to engage on the back, front and side wall upper projections 14' as understandable from Fig. XVIII, more particularly; 70 while the upper part of the block 51 is also con- 75

veniently grooved out at 53 to tapering rectangular cross-section.

The crown 24', instead of being made in complementary halves, comprises alternating narrow and relatively wider transverse sections 54, 55, respectively; said sections being supported at the abutting faces by spacer blocks 21'. It is also to be noted the sections 54, 55 are arched in the direction of their greater dimension to bridge the retainer side walls 49. Each end section 54 embodies a stop wall 56, and all sections 54 and 55 are individually provided with grooves 27' and associated apertures 28'; while the central section 55 is fitted with a water-back 31' having an inlet connection 33' and an outlet pipe 34'; and said sections 54, 55 are appropriately shaped to provide a continuous rib 26' along the retainer side and back walls 49, 48, respectively.

Engaging on the ribs 26' of the side walls 49 are the inverted channel-section base portions 57 of baffles 58 inclined to the horizontal and overlapping at the contiguous ends to define upwardly-inclined choke passages 47' whereby the heater flame is directed towards the top rear portion of the combustion chamber 3'. The corner baffles, see Fig. XVII, are of special form, that is to say they are made in right-and-left hand pairs with a rectangular groove 59 in the base 60, and a baffle blade 61 inclined to the horizontal projecting upwardly from the outer walls, said blades 61 convergently overlapping outwards at the angular intersection 62. Intermediate the corner baffle bases 60, along the back wall 48 of the retainer 10', and seating on said back wall rib 26' are the grooved bases 63 of overlapping alternate ridged, and grooved, baffles 64, 65, respectively, which jointly define convergent choke-passages 66, effective to direct incandescent gases passing upwardly there-through against the rear angular upper portions of the combustion chamber 3', a region heretofore inadequately heated and frequently many degrees lower in temperature than other parts of the combustion chamber, with resultant loss in thermal efficiency.

Obviously, instead of sustaining the pitched baffles 40, or 58, 61, 64 and 65, perimetrically around the crown 24 or 24', respectively, they may be by slight modification applied around the top of the structure 10 or 10'; also more than one such series of pitched blades may be applied at different levels of said structures and in staggering relation.

In operation, when the oil burner 8 is "on" the ascending, flame will heat up the retainer 10 or 10' to a high degree of incandescence in the minimum of time and by thermal attraction draw said flame through the slots 13, 12 outwardly and evenly against the inner wall of the jacketed combustion chamber 3, or through slots 13', 12' against the side and back walls respectively of the combustion chamber 3'. In the embodiment of Figs. I-X, further flame will be drawn outwardly through the transverse openings "O" defined by the top edges of the sections 11, underside of the crown 24 and spacer blocks 21; for whorling circulation over the baffles 40 and through the choke passages 47 defined thereby, and thus diffuse the flame completely over the inner wall of the combustion chamber 3, as well as evenly below the water head 6; and in addition thereto jets of flame will be directed upwards through the spaced apertures 28 against the water-back 31. In the modified form of the invention shown by Figs. XI-XIX, flame will

pass outwardly through the slots 13', 12', as above set forth, while that drawn through the side openings O' under the baffles 58, 61, and through the choke passages 47' will be distributed inwardly and rearwardly over the underside of the water head 6' to commingle with that issuing upwardly through the spaced apertures 28' in the crown 24'; whereas the choke passages 66 defined by the rear baffles 64, 65 will direct convergent strip-like jets of flame into the upper angular rear region of the combustion chamber 3'. Thus it will be seen that with either form of the invention shown and described, the differing directional diffusion of the flame set up by the devices 10 or 10' positively ensure effective distribution of said flame against the entire inner walls of the combustion chamber with substantially even thermal effect throughout the chamber.

While there has been described typical embodiments of this invention, it is obvious that modifications therein may occur to those conversant with the art, hence it is desired to include within the scope of the following claims all such reasonable variations in structural detail and combinations of the several parts as the state of the prior art may permit.

Having thus described my invention, I claim:

1. In an intermittently fired furnace having a fire pot below a combustion chamber with a substantial heat storing and flame diffusing device within the combustion chamber; a crown for the device having spaced apertures therethrough; serially arranged rigid baffles individually pitched to the horizontal with edge overlaps, spaced blocks having their lower portions suitably formed for retaining engagement with the top of the diffuser device, said blocks serving to support the crown at predetermined elevation above the device and defining intervening openings for auxiliary outlet of combustible gases, a suitable water-back sustained centrally of the apertured crown aforesaid; and the pitched baffles and edge overlaps serving to effect turbulent flow of combustible gases passing out of the block intervening openings through and over the baffles about the water-back as well as against the combustion chamber surrounding inner and top surfaces.

2. In an intermittently fired furnace having a fire pot below a combustion chamber, a massive cage-like heat storing and flame diffusing device located in said chamber with provision of surrounding clearance; an arched crown of complementary sections supported above the cage device by spacer blocks having engagement on said device to define intervening peripheral openings, said crown embodying a perimetric rib and the respective sections having grooves in the underside merging into respectively associated apertures spaced about the medial part of the crown; a water back removably applied to the crown with inflow and outflow connections; and laterally projecting rigid baffles supported by the crown perimetric rib, said baffles having edge overlaps defining passages of predetermined angularity and serving jointly with the baffles to effect local gyration of combustible gases flowing outward therethrough and over the water-back for direction against the combustion chamber inner and top wall surfaces.

3. A heat storing and flame diffusing device according to claim 2, in which the cage comprises complementary slotted sections having a lateral apertured lug at one side with spaced similar lugs at the opposite side, and means whereby the

- several section apertured lugs are connectible to those of the flanking sections.
4. A heat storing and flame diffusing device according to claim 2, in which the cage comprises 5 opposing rectangular vertically slotted sections with one of said sections blank, a single apertured lug at one side of each section with spaced similar lugs at the opposite side, and pins whereby the several section lugs are interconnected to 10 those of the flanking sections.
5. A heat storing and flame diffusing device according to claim 2, in which the baffles each embody a channel-section base, and a laterally-projecting blade portion inclined to the horizontal, 15 said blade portion projecting beyond the base at one end to define an overlap forming a choke passage thereat when the baffles are arranged in adjoining assembly, and the channel section base providing an interlock for adjoining cage section edges.
6. A heat storing and flame diffusing device according to claim 2, in which some of the baffles have ridged blades and others are grooved, said baffles when alternately assembled in lapping relation jointly defining convergent flow passages 25 therebetween.
7. A heat storing and flame diffusing device according to claim 2 characterized by corner baffles having a suitable-section groove in the 30 base corresponding to the corner angularity, and a blade portion inclined to the horizontal projecting from the outer faces of the base, said blades convergently-overlapping outwards along their adjoining edges to define a flow restrictive 35 passage thereat.
8. A heat storing and flame diffusing device according to claim 2 in which the crown supporting blocks are of special section with one portion defining a rectangular groove, and the other portion an opposing fork-like section.
- 40 9. A heat storing and flame diffusing device according to claim 2 characterized by corner crown supporting blocks, each said block embodying a channeled portion of corresponding angularity to that of the corner, and the other portion a complementally disposed upwardly tapering groove, and said channeled portion serving to connect adjoining cage section edges against lateral displacement.
- 45 10. A heat storing and flame diffusing device according to claim 2, in which the water-back is of hollow semi-spherical cross-section and is
- provided with a flat top, an annular concentric rib projecting below the water-back for seating engagement in the crown, means affording attachment of an inlet connection axially below the back, and differentially located means for accommodating outlet connections at different levels.
11. The combination with an intermittently fired furnace having a fire box with a burner at the bottom of its combustion chamber, of a 10 metallic heat diffusing and retaining device positioned axially over and of a greater overall diameter than the fire box, said device being in the form of a massive open bottomed cage somewhat smaller in height and girth than the combustion 15 chamber and provided perimetrically of its top with a series of mutually overlapping laterally projecting vanes which, during the active periods of the burner, induces diffusion and gyration of the hot products of combustion and at the same 20 time retards escape of said products from the space between the device and the furnace wall to facilitate heat absorption by said device, and which, during the off periods of the burner, operates to conserve the heat previously stored in 25 the device.
12. The combination according to claim 11, wherein the vanes incline upwardly toward the furnace wall.
13. The combination according to claim 11, 30 in which the top of the device has the form of a crown.
14. The combination according to claim 11, in which the top of the device is in the form of a crown and provided with multiple diffusing 35 apertures.
15. The combination according to claim 11, in which the top of the device is in the form of a removable cover, and in which the vanes are 40 detachably connected to said cover.
16. The combination according to claim 11, wherein the top of the device has radial grooves at the inside leading to gas escape apertures, and wherein baffle vanes incline upwardly toward the furnace wall.
- 45 17. The combination according to claim 11, wherein the top of the device has the form of a dome with multiple gas escape orifices, and wherein a counter rounded gas diverting element is superposed axially of the dome with its bottom surface overhanging said apertures.

GEORGE FAULDS.
